UNITED STATES PATENT OFFICE.

CARL H. DONNER, OF SUMMIT, NEW JERSEY.

MACHINE FOR CLEANING HAIR AND OTHER FILAMENTARY MATERIAL.

Application filed May 19, 1926. Serial No. 110,134.

This invention relates, generally, to improvements in machines for cleaning hair and other filamentary material; and the invention has reference, more particularly, to a continuously operating machine adapted to receive the material to be cleaned, subject the same to a cleaning operation, and progressively discharge the cleaned material out of the machine.

The invention has for its principal object to provide a very simple but highly efficient mechanism for the continuous treatment of hair, such as is used in the manufacture of hat and other felts, or generally for the treatment of any other kind of filamentary material, whereby dirt, "shorts" and other undesirable similar elements which may be contained therein, may be quickly and rapidly removed therefrom, and the machine is so constructed and arranged as to be continuously operating, i. e. so that the material may be continuously fed thereto, subjected to the cleaning operation during its movement through the machine, and when thoroughly clean automatically discharged from the machine into suitable receptacles disposed for its reception. To the above stated ends, the invention provides a housing to enclose a beating or agitating roll, said housing having a perforated wall or partition screen spaced beneath and substantially concentric to the roll, and said roll having disposed around its cylindrical surfaces peculiarly arranged and constructed radial agitating blades, which are adapted to both agitate the material to shake out the dirt, etc., as well as to propel or move the material toward a discharge opening in the end of the housing for ejection of the cleaned material from the machine. The machine is also provided with means for delivering the material into the housing; and, if desired, means cooperative with the discharge opening of the housing may be provided for conveying the cleaned material for deposit into suitable receptacles.

In the accompanying drawings, the invention is illustrated in one preferred form and by way of example; but it will be obvious that many alterations and variations may be made therein and in its mode of operation, which will still be comprised within its spirit; hence, it is to be understood that this invention is not limited to any specific form or embodiment, except in so far as specified in the claims appended hereto.

The invention is clearly illustrated in the accompanying drawings, in which:

Figure 1 is a plan view of the novel hair cleaning machine, with parts thereof in horizontal section; Figure 2 is a vertical longitudinal section thereof; Figure 3 is a vertical cross section, taken on line 3—3 in Figure 1; Figure 4 is a fragmentary side elevation at one end of the means for driving the hair feeding mechanism; and Figure 5 is a fragmentary side elevation at the opposite end of said means for driving the hair feeding mechanism.

Similar characters of reference are employed in the above described views, to indicate corresponding parts.

Referring now to said drawings, the reference character 6 indicates a suitably constructed housing, provided with any desirable form of supporting frame-work 7. Journaled in bearings 8, carried by the frame-work 7, is a main shaft 9 which extends longitudinally through the interior of said housing 6, from end to end thereof. Fixed on said shaft 9 so as to be rotated thereby, and arranged to be substantially coextensive with the length of the housing interior, is a beater cylinder or drum 10. Affixed to said cylinder or drum 10, so as to be disposed around the same in a helical line extending from one end thereof to the opposite end thereof, are a multiplicity of radially projecting agitating or beater blades 11, the same being pitched at angles oblique to the cross-sectional plane of the cylinder or drum, and in such relation to the direction of rotation of the latter as to effect a progressive longitudinal movement of the material delivered into the housing from one end thereof to the other as said cylinder or drum rotates and thus revolves said blades in contact with said material within the housing. Preferably the walls of the housing 6 are shaped so as to be concentric to the cylinder or drum 10, and spaced therefrom for a distance but slightly greater than the length of the projecting agitating or beater blades 11, so that sufficient clearance is provided for the latter. Arranged at the lower end of the housing 6 and concentric to the cylinder or drum 10 and its agitating or beater blades 11, but spaced so as to just clear the ends of the latter, is a perforate bottom wall, preferably in the form of wire screen mesh 12. Removably arranged beneath said bottom wall or screen 12 is a re-

ceptacle or box B to receive the dirt which is removed from the material undergoing cleansing treatment within the housing and discharged through said wall or screen.

5 Said housing 6 is provided in its forward side adjacent to one end and bordering the bottom wall or screen 12 with a material delivery opening 13. Coincident with and extending outwardly from said delivery opening 13 is a suitably supported feed trough 14, in the bottom of which is mounted a movable delivery apron or endless belt 15, which runs over and between rollers 16 and 17. The roller 16 serves as a driver for said 10 apron or belt, and is mounted on a driven shaft 18, journaled in and extending between the sides of said trough 14, which is rotated by a driving pulley 19 from any suitable source of power, or otherwise actuated as 15 may be desirable or convenient. Cooperating with the discharge end of said apron or belt 15, and disposed above the same is a feed roller 20, which is mounted on a shaft 21 journaled in and extending between the sides 20 of said trough 14. Disposed intermediate said delivery opening 13 and the discharge end of said apron or belt 15 are an additional pair of cooperating feed rollers 22 and 23, respectively mounted on shafts 24 and 25, 25 which are also journaled in and which extend between the sides of said trough 14. The several feed rollers 24, 25 and 20 are preferably driven from said driven shaft 18 by suitable transmission gearing. For example, 30 fixed on said driven shaft 18 is a spur gear 26 which meshes with and drives a spur gear 27 on the shaft 24 of the feed roller 22. On the opposite end of said shaft 24 is fixed a spur gear 28 which meshes with and drives a spur gear 29 on the shaft 25 of the feed roller 23. It will thus be apparent that the 35 cooperating rollers 22 and 23 will be driven in the direction of the arrows shown in Figure 3, whereby they serve to progressively feed the material to be cleaned from the delivery belt or apron through the delivery opening 13 into the interior of the housing 6. Also mounted on the shaft 25 is a second spur gear 29' which meshes with and drives 40 an idler gear 30, the latter in turn driving a spur gear 31 fixed on the shaft 21, thus rotating the roller 20 to cooperate with the apron or belt 15 in delivering the material fed by the latter to the rollers 22 and 23. 45 The material to be cleaned may be deposited on the delivery apron or belt 15 either by hand or by the aid of any suitable auxiliary mechanism (not shown) found desirable.

Provided in the end wall of the housing 6, opposite to the end adjacent to which the material delivery mechanism is located, is a discharge opening 32 arranged at the end of the perforate wall or screen 12. Preferably this discharge opening 32 communicates with 50 an enclosed chamber 33, which is provided

with a conveyer belt or apron 34 leading from said discharge opening 32 into the interior of said chamber 33, the same running over and between the rollers 35 and 36. Means are provided within said chamber 33 70 adjacent to the outer end of said conveyer belt or apron 34 for placing a suitable receptacle to receive the cleaned material. As shown in the drawings, the receptacle may be in the form of a bag 37, which is adapted to be suspended from hooks 38 in open arrangement adjacent to the discharge end of the conveyer; said hooks 38 being affixed to the frame-work of the chamber 33 in suitable locations.

80 The cylinder or drum 10 may be driven by means of a driving pulley 39 mounted on the exterior end of the shaft 9. Said shaft 9 may also be utilized as a source of power for driving the discharge conveyer 34, the driving roller 35 of which may be fixed on a shaft 40 having a driving pulley 41 on its exterior end. Mounted in bearings 42 attached to the housing frame-work 7 is a lay shaft 43. Fixed on said main shaft 9 is a pulley 44 to actuate a transmission belt 45 engaging a pulley 46 on one end of said lay shaft 43. On the opposite end of said lay shaft 43 is a pulley 47 adapted to drive a belt 48 engaging said pulley 41, thus transmitting actuating power to said discharge conveyer 34.

85 Fixed to the rearward side wall of said housing 6 are a plurality of inwardly projecting comb-fingers 49 which extend toward the cylinder or drum 10 so as to straddle the paths of movement of the agitating or beater blades 11. These comb-fingers 49 border the off-side of said perforate wall or screen 12 and serve both to remove the material under treatment from the blades 11 as the latter 90 revolve, and at the same time tend to prevent the material from being carried around with cylinder or drum, so that the same is maintained, while under agitation and movement, in contact with the said perforate wall 95 or screen.

95 In operation, the hair to be cleaned is delivered upon the delivery belt or apron 15 to be conveyed toward the delivery opening 13, the same being engaged by the feed rollers 20, 22 and 23 to be gradually and continuously fed thereby through said delivery opening into the interior of the housing 6. The cylinder or drum 10 being in motion, and rotating in the direction of the arrow 100 α in Figure 3, causes the hair thus introduced to be moved by its agitating or beater blades 11 across the perforate wall or screen 12, said blades 11 at the same time stirring or agitating the hair to loosen the same, thereby releasing the dirt, "shorts" and other foreign material therefrom for gravitation through the perforate wall or screen 12 into the dirt collecting receptacle or box B. At 105 the same time the oblique inclination or 110

pitch of said blades 11 produces a gradual longitudinal shifting of the hair, being thus subjected to the cleansing process, along the perforate wall or screen 12, which also agitates and stirs up the same to further aid in releasing the dirt etc., therefrom. In this manner, while the hair is subjected to the cleansing operation it is progressively moved through the housing 6 toward the discharge opening 32. The length of the housing and agitating or beater roll is so calculated that, by the time the hair, in its longitudinal progress, reaches said discharge opening 32, the same is substantially relieved of or cleansed from dirt, "shorts" etc. As the clean hair issues through the discharge opening 32, it falls upon the conveyer belt 34, and by said belt is carried outward for discharge into the receptacle 37 placed at the discharge end of said conveyer belt for its reception.

From the above description, it will be quite apparent, that the machine may be kept in continuous motion, while the material to be cleaned is fed thereto, so that the material will be subjected to thorough cleaning, and while being cleaned progressively propelled toward the machine outlet, through which it is automatically discharged when the cleaning thereof is complete.

It will be obvious that the machine is very simple, and yet performs by a mode of operation calculated to thoroughly loosen up the hair to beat out and discharge dirt, etc., therefrom. It will also be understood that the machine is adapted for use in cleansing materials other than hair, as for example vegetable or animal fibers, filamentary material and the like.

As hereinabove stated, the improved clean-

ing machine is shown in the drawings in one preferred form and by way of example, but it will be understood that many changes and modifications will suggest themselves to those skilled in the art without departing from the scope of this invention.

Having thus described the invention, I claim:

1. A machine of the kind described, comprising a housing, a rotatable drum longitudinally mounted in said housing, said housing being substantially concentric to said drum, said drum having a plurality of radially projecting agitating and propelling blades arranged in a helical line around its surface from end to end thereof, a perforate bottom connected with said housing to extend longitudinally beneath said drum and spaced to just clear the ends of said blades, said housing having on one side a lateral material intake opening above said perforate bottom and adjacent to one end of said drum, said housing having at its opposite side a row of inwardly projecting comb elements coincident in length to the length of said drum and adapted to cooperate with the blades of the latter, and said housing having a material discharge opening at an end thereof adjacent the opposite end of said drum and bordering said perforate bottom.

2. A structure as specified in claim 1, in combination with means for progressively delivering material for treatment through said housing intake opening.

In testimony, that I claim the invention set forth above I have hereunto set my hand this 12 day of May, 1926.

CARL H. DONNER.
